UNITED STATES PATENT OFFICE

128,977

DESIGN FOR AN ARTICLE OF BRIC-A-BRAC

James Matrick, Portsmouth, N. H.

Application May 31, 1941, Serial No. 101,248

Term of patent 14 years

To all whom it may concern:

Be it known that I, James Matrick, a citizen of the Union of Socialist Soviet Republics, residing at Portsmouth, in the county of Rockingham and State of New Hampshire, have invented a new, original, and ornamental Design for an Article of Bric-a-Brac, of which the following is a specification, reference being had to the accompanying drawing, forming a part thereof.

Fig. 1 is a perspective view of an article of bric-a-brac showing my new design; and
Fig. 2 is a section on the line 2—2 of Fig. 1.

I claim:

The ornamental design for an article of bric-a-brac, substantially as shown.

JAMES MATRICK.
